REFRIGERATOR SHELF

William I. Hamby, Great Neck, N. Y., assignor
to Servel, Inc., New York, N. Y., a corporation
of Delaware

Application July 23, 1935, Serial No. 32,742

9 Claims. (Cl. 211—147)

This invention relates to refrigerator shelves and it is an object of the invention to provide an improved shelf which may be readily removed from or adjusted to different positions in a refrigerator cabinet.

It is a further object to provide a refrigerator storage compartment which is free of projecting shelf supports and, therefore, neat in appearance and easy to keep clean.

The invention, together with the objects and advantages thereof, will appear upon consideration of the following description taken in conjunction with the accompanying drawing forming part of this specification and of which:

Fig. 1 is a plan view of a portion of a refrigerator shelf and a section of a refrigerator storage compartment wall illustrating an embodiment of the invention;

Fig. 2 is a sectional view on line 2—2 in Fig. 1;

Fig. 3 is a sectional view on line 3—3 in Fig. 1; and

Fig. 4 is a view like Fig. 3 showing the shelf support in operated position.

Referring to the drawing, there is illustrated one corner of a refrigerator shelf and an adjacent portion of the inner wall of a refrigerator. It will be understood that the shelf is supported by the wall of the refrigerator at a desired level by means of a suitable number of shelf supports. In the interest of clarity in this disclosure, only one of the several like shelf supports is here illustrated.

Referring more particularly to Fig. 1, a refrigerator shelf 10 comprises a peripheral wire frame 11 having struts 12 extending the width of the shelf and supporting suitable rods or ribbons 13 which extend in the direction of the depth of the shelf. The peripheral frame 11 and struts 12, in the present embodiment, are rectangular in cross-section, and the bars or ribbons 13 are relatively flat. Secured to the shelf 10 is a member 14 which may be referred to as a shelf support, and which projects from beneath one side of the shelf into a suitable indentation 15 in the liner or side wall 16 of the refrigerator storage compartment. It will be understood that the shelf 10 is provided on each side with, for instance, two supporting projections like the shelf support 14, and that the liner or storage compartment wall 16 is provided with a corresponding number of indentations at the desired level, so that the shelf 10 is supported in the refrigerator storage compartment at a level determined by the level of the indentations 15.

The shelf support 14, as may be seen by referring to Figs. 1 to 3 inclusive, comprises a member

17 attached to the shelf 10 by means of a resilient strip 18 which may be referred to as a spring leaf. The projecting end of the member 17 is preferably rounded to conform to the shape of the indentation 15. The other end of the member 17 extends beneath one end of a frame strut 12. The member 17 is recessed on its upper surface to receive the end of the strut 12 and the adjacent portion of the peripheral frame 11. The recessed upper surface of the member 17 is formed to provide two flanges 20 which extend upwardly, one on each side of the frame strut 12 behind the peripheral frame member 11. One end of the spring leaf 18 is attached to the strut 12, as, for instance, by rivets 19. The other end of the spring leaf 18 is connected to the member 17. The lower side of the member 17, which is inclined upwardly in the direction of the shelf, may be formed with a groove, as shown, to receive the intermediate portion of the spring leaf 18. The member 17 may be formed of any suitable material as, for instance, molded Bakelite or hard rubber. If the member 17 is formed by a molding process the end of the spring leaf 18 may be secured thereto by molding with the end of the spring leaf as an insert.

When the shelf 10 is in position in a refrigerator cabinet, the end of the shelf support member 17 is engaged in an indentation 15 and the edge of the shelf rests in the upper recessed surface of the member 17. From the above description, it will be understood that the shelf support 14 is, in effect, resiliently pivoted or hinged to the underside of the shelf at a point set in from the edge of the shelf. To remove the shelf 10, each of the shelf supports may be flexed downwardly against the action of the spring leaf 18, as illustrated in Fig. 4, thereby disengaging the member 17 from the indentation 15. The flanges 20 on each side of the strut 12 act as guides, preventing twisting or lateral movement of the support. In order that the level of the shelf 10 in a refrigerator cabinet may be adjusted, the liner or refrigerator compartment wall may be provided with a further set of indentations 15' at a different level. It will be understood that any number of sets of indentations may be provided.

Various changes may be made within the scope of the invention as indicated by the following claims.

What is claimed is:

1. A refrigerator shelf including a support member located beneath said shelf and projecting beyond an edge of the shelf to engage a wall of a refrigerator storage compartment, and resil-

- ient means connecting said member to said shelf, said resilient means normally holding said support member against the bottom of said shelf but permitting said member to be flexed in a downward arcuate path for disengagement from said refrigerator wall.
5. A refrigerator shelf including a support member located beneath said shelf, and a resilient member having one end attached to said support member and the other end attached to the under side of said shelf at a point set in from the edge of the shelf, said resilient member normally holding said support member against the bottom of said shelf with one end of said support member projecting beyond an edge of the shelf for engagement with a projection on a wall of a refrigerator storage compartment, but permitting flexure of said support member in a downward arcuate path for disengagement from said wall projection.
10. 3. In a refrigerator shelf adapted to be supported by side walls of a refrigerator storage compartment, a support member located beneath said shelf, and a resilient member joining said support member to said shelf, said resilient member normally holding said support member against the bottom of said shelf with a part of said support member projecting beyond the edge of said shelf to engage a refrigerator wall, and said resilient member permitting flexure of said support member downward and away from said wall to permit release of said shelf.
15. 4. In combination, a refrigerator shelf, a shelf support member hinged on the bottom of said shelf at a point set in from the edge of said shelf, and a resilient member connected to said shelf and said shelf support, said resilient member being arranged to urge said shelf support against the bottom of said shelf with a portion of the shelf support projecting beyond an edge of the shelf but permitting said shelf support to be swung downward to facilitate adjustment of said shelf or removal from a refrigerator storage compartment.
20. 5. In a refrigerator shelf, a supporting member located beneath said shelf, a leaf spring having one end connected to said shelf at a point set in from an edge of said shelf and the other end connected to said support member, said leaf spring urging said support member against the bottom of said shelf with a part projecting beyond an edge of said shelf for engagement with a refrigerator wall but permitting downward movement of said support member to facilitate disengagement from said wall.
25. 6. A refrigerator shelf including a generally rectangular frame having struts, cross bars supported on said frame, a support member of molded material arranged so that an edge of the shelf rests thereon, and a resilient member
- having one end embedded in said support member and the other end attached to the underside of one of said frame struts at a point set in from the edge of the shelf to permit downward flexure of said support member for disengagement from a wall of a refrigerator storage compartment, said support member having flanges at its upper edge forming a vertical guide on each side of said strut and having a groove along its lower edge to receive said resilient member.
30. 7. A refrigerator shelf provided with a plurality of supporting means adapted to engage opposite walls of a refrigerator storage compartment for maintaining the shelf in stable position therein, each of said supporting means at one side of the shelf comprising a member extending beyond an edge of the shelf and having a flat upper surface and an inclined lower surface, the flat upper surface being adapted to bear against the under side of the shelf, and means including a resilient leaf spring fixed to the shelf and the inclined lower surface of said member for flexing said member downwardly in a vertical plane.
35. 8. A refrigerator shelf comprising a substantially rectangular-shaped frame, bars spaced from and parallel to two opposite sides of said frame and normal to the opposite opposing sides thereof, a plurality of supporting means adapted to engage opposite walls of a refrigerator storage compartment for maintaining the shelf in stable position therein, each of the supporting means at one side of the frame comprising a member extending beyond a side of the frame and having a flat upper surface portion adapted to bear against the under side of a bar and an inclined lower surface portion, said member having a vertical surface portion adjacent the upper flat portion adapted to bear against an outer edge of a side of the frame, means including a resilient leaf spring fixed to the bar and the inclined surface of the member to provide a pivotal connection for flexing said member downwardly in a vertical plane, and upwardly extending flanges fixed to each side of said member between the pivotal connection and the inner edge of a side of the frame to provide a vertical guide at each side of the bar.
40. 9. A refrigerator shelf provided with a plurality of supporting means adapted to engage opposite walls of a refrigerator storage compartment for maintaining the shelf in stable position therein, each of said supporting means at one side of the shelf comprising a member extending beyond an edge of the shelf and being notched at the upper surface thereof to provide surface portions adapted to bear against the under side and the outer side edge of the shelf, and means fixed to the shelf and said member to provide a pivotal connection for the latter.
